UNITED STATES PATENT OFFICE.

WILLIAM HILL, OF ALEXANDRIA, LOUISIANA.

COTTON-COMPRESS.

1,230,709.

Specification of Letters Patent. Patented June 19, 1917.

Application filed January 12, 1916. Serial No. 71,699.

To all whom it may concern:

Be it known that I, WILLIAM HILL, a citizen of the United States, and a resident of Alexandria, in the parish of Rapides and State of Louisiana, have invented a new and Improved Cotton-Compress, of which the following is a full, clear, and exact description.

The invention relates to improvements in presses and more particularly to compresses of the general design and construction disclosed in Patent No. 1,062,465, issued to me May 20, 1913, and in Patent No. 1,164,519 issued to me December 14, 1915, to which 15 patents cross reference is here made.

An objection has existed in the operation of the presses in that the material when treated by the said presses extends laterally from between the platens of the press, there- 20 by increasing the bulk of the bale and forming margins of material having a density different from the density of the body of the bale. It is the principal object of the present invention to overcome this objection 25 and to provide a compress to prevent the lateral extension or flow of the material under pressure.

Drawings.

30 Figure 1 is a side view of a compress constructed and arranged as in accordance with the present invention; and

Fig. 2 is a top plan view showing on an enlarged scale confining sides and operating 35 mechanism therefor.

Description.

As fully set forth in the patent and application for patent above mentioned, a 40 compress is employed to further reduce by pressure the bulk of cotton bales. To this end, a head platen 7 and a base platen 8 are moved together by a pressure applied to said platens, by a relatively quick acting medium, 45 such as steam introduced in a cylinder 9 and by a relatively slower medium, such as water introduced into a hydraulic ram 10. The pressures thus employed are primarily imposed on the platens 7 and 8 successively. 50 Both platens are impelled to move in equal degree by a connecting transmission mechanism employing link arms 11, lever arms 12, which are integrally connected with gear segments 13 and pivoted therewith on stud 55 shafts 14 in a standing frame 15. As seen best in Fig. 1 of the drawings, the segments 13 are operatively connected with gear racks

16 on a plunger 17, which enters the hydraulic ram 10, as more fully described in the patent and application referred to. When 60 steam is admitted to the cylinder 9, the platens 7 and 8 are moved rapidly toward each other and upon the bale of cotton or other material which has been placed on the platen 8. The force expended by the steam 65 is relatively slight and the movement of the platens is soon arrested by the resistance of the bale. A preliminary pressure, however, of a greater or less degree is effected by the steam and in a relatively quick period of 70 time. Water is drawn into the ram 10 by the movement of the plunger 17 thereof and when the resistance of the bale overcomes the force of the steam, the further movement of the platens is induced by the pressure 75 exerted thereon by the operation of the hydraulic ram 10. The synchronism of the two platens is maintained by the same means, to wit, the link arms 11 and lever arms 12. The relatively slow, but intense 80 pressure exerted by the ram 10 is continued until the bale is compressed to the desired thickness between the two platens.

The sides of the bale while undergoing the action above noted, being heretofore unrestrained, the material has to greater or lesser degree extended laterally from between the 85 said platens 7 and 8.

In the present invention, the material under treatment is prevented from flowing 90 from between the platens 7 and 8 and at the longer sides thereof, by the sides 18, which are pivotally mounted by hinge pins 19 in brackets 20, fixedly mounted on the standing frame 15 and at one side thereof. 95 To reinforce the sides 18, each side is furnished with ribs 21, as seen best in Fig. 2 of the drawings. Operatively connected with the ribs 21 by hinge bolts 22 are toggle plates 23. The plates 23 are pivotally connected by hinge bolts 24 with toggle links 25. The said links are pivotally connected by the pins 26 between the extension frames 27 and at the outer ends thereof.

The frames 27 are centrally united by a 105 cylinder 28 bored to house a power cylinder 29, to which steam is admitted from a suitable source by way of a supply pipe 30, as seen best in Fig. 1 of the drawings. Between the extension members of the frames 110 27, the connecting arms 31 extend and move when swinging about the pivots formed by the bolts 24 and 32, with which the said arms are connected. The bolts 32 are set in

the ends of a cross head 33 which is operatively connected with the piston rod 34 and to support and aline which the runways 35 are provided.

- 5 Within the cylinder 29, a piston 36 is mounted and suitably packed to be moved by the steam which is admitted thereto, and in accordance with the throw of the throttle lever 37, which controls a valve in a 10 steam chest 38 adapted to be selectively operated for introducing the steam at one or the other side of the piston 36. The steam exhausted from the cylinder 29 is conveyed away by the exhaust pipe 39.

15

Operation.

The operation of a compress thus constructed is as follows: The bale having been disposed between the platens 7 and 8 and 20 the old bands thereof having been removed and new bands having been properly disposed, the sides 18 are closed on the bale and locked in operative position and preferably preliminary to the introduction of 25 power to the cylinder 9 and ram 10.

To accomplish the above result, the attendant manipulates the lever 37 to introduce steam to the cylinder 29 at the outer side of the piston 36. The piston 36 and 30 cross head 33 connected therewith and the arms 31 are moved forward. When the sides 18 are inactively disposed they are swung back on the pins 19 until they are parallel with the frames 27 or are in position to 35 clear the entrance to the platens 7 and 8. In this position of the frames, the piston 36 is at the forward end of the cylinder 29 and the toggle plates 23 and links 25 are collapsed, the toggle breaking in the 40 direction indicated by the arrows in Fig. 2 of the drawings. When the steam is introduced to the cylinder 29 as above stated, the toggle plates 23 and links 25 are extended to their active position, as best shown 45 in Fig. 2 of the drawings, where it will be noted the bolts 24 are carried beyond a straight plane intersecting the centers of bolts 22 and pins 26. In this position, the toggles formed by the plates 23 and the links 50 25 are locked by any subsequent pressure exerted on the sides 18 and when the cross head 33 is held from further movement.

The sides 18 being thus moved to compress the bale and to planes coincident with 55 the side edges of the platens 7 and 8, power is applied to the cylinder 9 and ram 10, with the result that the platens are moved toward each other, first, with relatively greater speed and less power, and subsequently with greater power and less speed 60 until the bale is compressed to the desired density and dimension. It is obvious that during this pressure, any tendency on the

part of the material forming the bale to extend from the long sides of the platens is 65 opposed by the sides 18, which are locked immovably during the movement of the platens 7 and 8.

After the bale has been compressed, the sides 18 are swung back, as the result of the 70 operator manipulating the lever 37 to admit steam to the opposite end of the cylinder 29, when the power applied to the piston 36, will operate to force outward the cross head 33 in the direction shown by the arrow 75 in Fig. 2 of the drawings, pulling upon the arms 31 to break the lock of the toggle plates 23 and links 25.

After the sides 18 have been moved, the bale being secured against extension, is 80 released by the platens 7 and 8 and removed from the machine. It will then be seen that the rectangular form of the cross section of the bale has been preserved and that if any tendency to flow is present, it will be 85 manifest at the ends and not at the sides of the bale.

Claims.

1. A compress comprising a bale chamber having open sides and provided with extensions at its sides, compressing means working in said chamber, hinged wings for closing the open sides of the said chamber, a pair of toggle levers for the wings, one member of each pair of toggle levers being pivoted to a wing and the other member to an extension of the bale chamber, a power cylinder carried by said chamber, a piston in the cylinder, a cross head secured to the piston rod and having guided movement, and arms pivoted to the ends of the cross head and to the pivots connecting the members of the toggle levers. 90

2. A compress, comprising a supporting frame having an extension frame, platens 105 working in the frame, coöperating means for operating the platens, hinged wings for closing the sides of the frame, a pair of toggle levers for each wing, one member of which is pivoted to the wing and the other member to the extension frames, a power cylinder secured to the extension frame and having guideways projecting therefrom in alinement therewith, a piston in the cylinder, a cross head secured to the piston 110 rod and working in the said guideways, and arms pivoted to the ends of the cross head and to the pivots connecting the members of the toggle levers. 115

In testimony whereof I have signed my 120 name to this specification in the presence of two subscribing witnesses.

WILLIAM HILL.
